UNITED STATES PATENT OFFICE.

WILLIAM N. CRABTREE, OF PORTERVILLE, CALIFORNIA.

GUN LOCK

SPECIFICATION forming part of Letters Patent No. 229,383, dated June 29, 1880.

Application filed January 22, 1880.

To all whom it may concern:

Be it known that I, WILLIAM NEWTON CRABTREE, of Porterville, in the county of Tulare and State of California, have invented 5 a new and useful Improvement in Safety Gun- Locks, of which the following is a specification.

The object of my invention is to construct hair-trigger gun-locks with devices that will 10 prevent accidental discharge of the gun without requiring additional manipulation or interfering with the rapid handling of the piece; and the invention consists in a blocking-piece interposed between the hammer and breech, to 15 prevent contact of the hammer with the cap- tube, and a thumb-lever fitted upon the hammer to hold the blocking-piece out of action when the hammer is set for firing, the said de- 20 vices working automatically by the usual ma- nipulations of the hammer, as more particularly set forth hereinafter with reference to the accompanying drawings, wherein—

Figure 1 is an elevation of the lock mechanism with the hammer in a cocked position. 25 Fig. 2 shows the hammer as set in the safety position. Fig. 3 is a perspective view of the blocking-piece and stirrup.

Similar letters of reference indicate corresponding parts.

A is the hammer, hung on pin *a*, and formed 30 with the tail-piece *b*, to which the spring *c* is connected, to give the required tension. *B* is a stirrup hung by a pivot, *d*, to a back exten- 35 sion of hammer *A*, and extending at each side of the hammer and carrying the pivoted block- 40 ing-piece *C*, that lies upon the front face of the hammer. *e* is a spring fixed on the under side of hammer *A*, and bearing upon the end of stirrup *B*, to throw the piece *C* upward. *D* 45 is a thumb-lever pivoted by a screw-pin, *f*, on the side of hammer *A*, and extending in contact with the stirrup *B*, to prevent the same from rising, except as hereinafter described. *g* is a pin fixed on the side plate of the lock, 50 with which pin one side of stirrup *B* moves in contact as the hammer is moved, so that the blocking-piece is thrown downward as the hammer is cocked and left free to rise as the hammer falls.

The hair-trigger devices consist of an arm,

h, hung horizontally above the trigger *i*, and formed at its pivoted end with a shoulder, *l*. A piece, *k*, is hung on the tail-piece *b* of the ham- 55 mer, so as to move horizontally forward and back as the hammer moves, and fitted with a projection, *2*, that rides over and engages with the shoulder of the arm *h* when the hammer is cocked. A spring, *l*, tends to press the piece *k* downward, and *m* is the trigger-spring. A backward movement of trigger *i* frees the 60 moving end of arm *h*, and the pressure of pieces *k* on the shoulder *l* throws up the arm *h*, thereby freeing the shoulder *l* from the pro- 65 jection *2* and allowing the hammer to spring forward. This construction permits a very delicate action.

As the hammer *A* is drawn back to cock the gun the blocking-piece *C* is forced down by contact of the pin *g* with the stirrup *B*, and the end of the thumb-lever *D* in contact with *B* 70 retains the block *C* down when the hammer is thrown forward to fire the gun.

The stirrup *C* is formed with a notch or re- 75 cess, *3*, and when the thumb-lever *D* is moved so that its end is over the notch *3* the piece *C* is permitted to rise by the action of spring *e*.

The thumb-lever *D* is formed wider than the hammer, so that the ordinary pressure of cock- 80 ing the gun will move the other end of *D* over notch *3*, and a spring, *n*, returns the lever *D* when the pressure on the hammer is released.

Thus it will be seen that in firing the piece the hammer is cocked as usual, and when the trigger is pulled the piece *C* is kept out of the way, while if it is desired to set the hammer for 85 safety, it is simply let down as usual by hold- 90 ing it, and pressure of the operator's thumb on lever *D* allows the blocking-piece to come up between the hammer and breech and prevent contact of the hammer with the cap-tube, 95 as shown in Fig. 2.

I do not limit myself to the construction ex- 95 actly as shown and described, as the details of construction may be varied without depart- ing from my invention.

Having thus described my invention, I claim as new and desire to secure by Letters Pat- ent—

1. The safety device for gun-locks, consist- 100 ing of the pivoted blocking-piece *C*, hung by

stirrup B on the hammer, the spring e, fitted to throw the piece C upward, and the thumb-lever D, hung on the hammer and fitted to arrest or allow the movement of piece C, as shown and described.

2. In gun-locks, the combination, with stirrup B, having recess 3, the blocking-piece C, pivoted to stirrup, and the thumb-lever D,

pivoted on the hammer, of the spring n, bearing on the lever, and the pin g, bearing on the stirrup, as and for the purpose specified.

WILLIAM NEWTON CRABTREE.
